UNITED STATES PATENT OFFICE.

JOSEPH T. SALESSE, OF OTTAWA, ONTARIO, CANADA.

AWNINGS-ROLLER AUTOMATIC STOP

Application filed February 2, 1926. Serial No. 85461

This invention has relation to certain new and useful improvements in an awning roller automatic stop and has for its primary object the provision of a structure which is of simple construction and operation as well as highly efficient in use, and which may be employed for practically all awnings.

The invention has for another object the provision of an awning roller automatic stop which may be readily adjusted to cause automatic stopping of the rotation of the roller when the awning is unwound sufficiently, thus preventing wrapping or winding of the awning canvas in the wrong direction around the roller.

The invention has for its further object the provision of an awning roller automatic stop which is composed of the minimum number of parts of simple construction and arrangement and which will be highly efficient in use.

With the foregoing and other objects in view, as will appear as the description proceeds, the invention resides in the construction, combination and arrangement of co-operating elements as hereinafter more specifically set forth, claimed and shown in the accompanying drawings forming a part of the present application and in which:

30 Figure 1 is a perspective view of the roller in use.

Figure 2 is an enlarged perspective view of the roller, removed and with parts broken away.

Figure 4 is a view similar to Figure 3, showing a slightly modified form of the

40 Figure 5 is a transverse section, substantially on the plane of line 5-5 of Figure 4, looking in the direction indicated by the arrows.

45 Referring more in detail to the drawing, in which similar reference characters designate corresponding parts throughout the several views, it will be noted that the shaft of the roller is composed of sections 10 and 11, which are supported respectively in bracket bearings 12 and 13. The bracket bearings 12 and 13 have oppositely directed base portions or flanges 14 provided with suitable openings 15 to receive attaching members through the medium of the bracket bearings 50 12 and 13 may be firmly secured upon a wall or other support, as will be readily under-

stood by referring to Figures 1 and 2. It will also be seen from these views that the awning canvas 16 is wound upon the roller outer sleeve 17 in the usual manner or unwound from this sleeve by operation of the control shaft 18, the upper end of which extends into the bracket bearing 12 and has appropriate driving means with the shaft section 10. The shaft section 10 is rigid with the roller outer sleeve 17 and the roller core 19, on which the sleeve 17 is firmly mounted.

The shaft section 11 is adapted to be locked into the bracket bearing 13 after adjustment, as will be later more clearly understood, by a cotter pin 20 or other appropriate means, thus preventing rotation of the shaft section 11 during winding and unwinding of the awning canvas 16. The shaft section 11 extends in and through the end of the roller core 19 and is provided with a threaded portion 21 extended through the elongated pocket 22 provided in the roller core 19 and opening upon the inner face of the roller sleeve 17, the core 19 being practically of rectangular form in cross section throughout the greater portion of its length. The inner end of the shaft section 11 is extended through the transverse partition 23 in the core 19 and into the smaller or auxiliary pocket 24, a roller 25 being then secured upon the same, within the pocket 24 and firmly held on the inner end of the shaft section 11 by a pin 26 or the like extended through the collar 25 and through the inner end of the shaft section 11, as clearly shown in Figures 2, 3 and 4 of the drawings. A stop nut 27 works upon the threaded portion 21 of the shaft section 11 within the pocket 22 and travels back and forth on the shaft section 11 from one end to the other of the elongated pocket 22, the walls of the pocket 22 preventing turning of the nut 27 within the pocket 22. It will therefore be seen that rotation of the roller in either direction may be regulated by proper adjustment of the shaft section 11 to place the nut 27 a certain distance from one end of the pocket 22 before placing the cotter pin 20 through the bracket bearing 13 and the outer portion of the shaft section 11, as shown in Figure 2.

In the modified form of the invention shown in Figures 4 and 5, the core of the roller is constructed similar to the preferred form with the exception that it has a cap 110.

29 provided on its outer end with an annular flange 29^a carried thereon to receive the reduced end 28^a of the halves or longitudinal sections 28 of the sectional or two-part roller sleeve 17 which in this form may be made of wood or other appropriate material.

In both forms of the invention, the sleeve 17 may be secured to the core near the ends 10 of the latter by appropriate bolts 30, as illustrated in Figures 3 and 4, to thus cause rotation of the core 19 with the sleeve 17. It is believed the complete construction and operation of the invention may now be apparent 15 from the foregoing paragraphs taken in connection with the accompanying drawings without further detailed description. It may be briefly stated, however, that the stop nut 27 may be readily adjusted on the threaded 20 portion of the shaft section 11 or 11^a either before or after mounting of the roller in the bracket bearings provided for the end shaft sections 10, 11 or 11^a. The pin 20 may then be passed through the outer end of the sections 11 or 11^a and through the bracket bearing 25 in which such shaft section is mounted, thus holding the shaft section 11 or 11^a against rotation in its bracket bearing 13. During winding and unwinding of the awning 30 canvas 16 on the sleeve section 17, the stop nut 27 will work back and forth on the threaded portion of the shaft section by which it is carried and within the pocket 22 of the core 19, the stop nut 27 finally striking 35 upon one end wall of the pocket to prevent further rotation of the roller sleeve 17 and consequently winding or unwinding of the awning canvas 16. A slight change of the 40 adjustment of the nut 27 may be made by withdrawing the pin 20 and turning the shaft section 11 or 11^a with respect to other parts of the roller structure and then replacing the pin 20 to prevent further independent 45 rotation of the shaft section 11 or 11^a. This adjustment of the nut 27 will permit increase or decrease in the winding or unwinding of the awning canvas 16 as the roller sleeve 17

and core 19 are operated in the usual manner. It is also apparent that a roller constructed 50 in accordance with this invention will eliminate danger of the awning canvas 16 being only partly unwound or being wound upon the roller sleeve 17 in the wrong direction owing to continued rotation of the roller in the same direction after complete unwinding 55 of the awning canvas 16. Furthermore, when the present form of roller is employed, danger of the canvas awning 16 sagging when unwound, is overcome.

While the preferred embodiments of the 60 invention have been disclosed, it is to be understood that minor changes in the details of construction, combination and arrangement of cooperating elements may be resorted to within the scope of what is 65 claimed without departing from the spirit of the invention.

What is claimed is:—

A device of the character described including a roller sleeve, a shaft section rigid 70 with one end of said sleeve, a removable core fitted in the opposite end of said sleeve and secured thereto, said core having spaced pockets formed therein, a second shaft section loosely journaled in said core and extending longitudinally through said pockets and threaded for a portion of its length, bracket 75 bearings supporting the outer ends of said shaft sections, said second shaft section being normally secured in said bearing against 80 movement, means for rotating said roller sleeve and a nut working on the threaded portion of said second shaft, being disposed in one pocket of said core and adapted to contact with the side walls thereof, whereby 85 the rotation of the roller will cause the nut to travel on said shaft, said nut limiting the rotation of the roller upon contact with the end walls of said pocket, said second shaft being releasable from its bracket bearing to 90 permit adjustment of said nut on said shaft.

In testimony whereof I affix my signature.

JOSEPH T. SALESSE.
